BOAT LADDER

Donald C. Peters, 833 Oak Ave., and Yancey N. Juergenson, 401 E. 11th St., both of Davis, Calif.

Filed June 15, 1964, Ser. No. 80,380

Term of patent 14 years

(Cl. D71—1)

FIG. 1 is a front elevational view of a boat ladder, showing our new design;

FIG. 2 is a side elevational view; and,

FIG. 3 is an end elevational view thereof.

We claim:

The ornamental design for a boat ladder, as shown.
